F. L. ANTISELL

SKEW BACK FOR FURNACES

Filed April 28, 1923

Patented Apr. 7, 1925.

1,532,568

UNITED STATES PATENT OFFICE.

FRANK L. ANTISELL, OF PERTH AMBOY, NEW JERSEY.

SKEW BACK FOR FURNACES.

Application filed April 23, 1923. Serial No. 635,196.

To all whom it may concern:

Be it known that I, FRANK L. ANTISELL, a citizen of the United States, and a resident of Perth Amboy, county of Middlesex, 5 State of New Jersey, have invented certain new and useful Improvements in Skew Backs for Furnaces, of which the following is a specification.

This invention relates to an improved means for supporting the roofs of open hearth furnaces, the particular means consisting of an improved skew back for the roof so constructed and arranged that the major part of the skew back, including the 10 means for securing it to the I-beam buck stays, is exposed to the air so that it is in effect an air cooled furnace skew back.

Prior to my invention it was the general practice to construct a skew back of 15 the ordinary shape, the skew back being hollow so that water could be passed therethrough in order to water cool the same. This water cooling was necessary as the heat 20 of the furnace is in direct contact with the under surface of the skew back which resulted in the skew back extracting therefrom 25 an enormous amount of heat. It has been found by experience, however, that the water cooled structure is inefficient in practice.

Furthermore, the use of a water cooled skew back is not desirable because in the event of accident to the pumping equipment, or the freezing of the pipes, or for any other 30 reason, the water is shut off, the skew back will melt and the roof or arch will fall in.

I have overcome these objections by constructing an air cooled skew back.

Referring to the drawings in which the 40 same reference character indicates the same part in the several views:

Fig. 1 represents a vertical transverse cross section of the furnace showing the structure embodying my invention, parts being 45 broken away.

Fig. 2 is an elevation of the furnace and skew back structure, parts being broken away.

Fig. 3 is a perspective view of the skew 50 back embodying my invention.

In the drawing, A is the support, foundation or floor, B is the lower portion of the furnace structure, C is the roof of the furnace structure, and D is the door.

55 While the furnace structure is conventionally shown in the drawing, it is to be under-

stood that it is built in the usual way of fire-brick and fireproof material.

10 and 11 are the ordinary upright I-beam buck stays secured to the foundation A in the usual way at 12 and 13, the upper portions of the buck stays being joined by a tie rod 14, the two portions of the tie rod being connected by a turn buckle 15, as usual. The buck stays 10 are shown at the 15 front of the furnace, and 11 at the rear thereof.

The arched roof 13 of the furnace is supported by the walls of the furnace and the thrust is taken up by the member 16 consisting of a metal bar supported by the top of one of the walls and impinging against the buck stays 11 and so formed as to fit against and resist the thrust of the furnace arch at one side thereof. The arch of the 20 furnace is supported at the other side by the lower end 31 of the skew back 30, the lower portion 31 being formed at an angle to the main body 32 of the skew back which rests against the buck stays 10 and is secured thereto by bolts 35 and 36 at a point removed from the door of the furnace in a position to resist and hold the thrust of the arch B.

A strengthening rib 33 extends longitudinally along the inner surface of the skew back just above the supporting flange 31.

The upper portion 32 of the skew back being exposed to the air is consequently 25 cooled by the surrounding atmosphere, and the temperature is therefore a little above the temperature of the room.

Another feature of my improved skew back is due to the fact that the supporting flange 31 is beveled on its side at 34 which 30 facilitates the use of the charging machine when loading the furnace. In the event that the charging machine is too high it will strike against the sloping surface 34 of the air cooled skew back and be deflect- 35 ed downward into the furnace proper.

When the charge box came into contact with the vertical face of the old form of skew back the impact weakened the arch so that there was danger of it falling in 40 upon subsequent charges.

The door D is supported on hangers 40 and 41 secured to a horizontal rod 42, the ends of the rod at 43 and 44 engaging with guiding cam shaped grooves 51 and 52 in 45 supports 50 secured to the buck stays 10, as shown. Suitable hoisting means (not

shown) are used to lift the door in the direction of the arrows shown in Figs. 1 and 2. As the ends of the rod 42 engage the walls of the guide grooves 51 and 52 the door upon its being hoisted will be removed from the furnace mouth by the cam action of the ends of the rod 42 on the walls of the guide grooves 51 and 52, as clearly indicated, the door being thereby removed from the furnace mouth and lifted to a suitable position just above it.

By means of the construction of skew back above described it is apparent (1) that there is provided a structure of sufficient resistance above the line of thrust of the arch to withstand the stresses of the same, or, (2) that the securing points are above the line of pressure on the skew back, which latter is supported by the buck stays and impinges against them above the line of pressure, (3) that the skew back is of such a construction and so supported that the greater portion of its body or structure is in contact with the air and that it is in position to conduct the heat away from the furnace so that it may be absorbed by the surrounding atmosphere (4) and that by reason of its beveled edged formation just above the furnace mouth an efficient guiding means is present to engage the charging means when loading without danger of permanently destroying the structure due to the impact of the furnace charging means.

As changes of construction could be made within the scope of my invention it is intended that all matter contained in the above description or shown in the accompanying drawing shall be interpreted as illustrative and not in a limiting sense.

Having thus described my invention what I claim as new and desire to secure by Letters Patent is:

1. In a furnace having an arched roof

and upright buck stays, a supporting skew back having an upright plate resting 45 against said buck stays, a rib projecting from said plate opposite said buck stays and a downward extension of said plate below said rib inclined in a plane at a right angle to the thrust of said arch.

2. In a furnace having an arched roof and upright buck stays, a supporting skew back having an upright plate resting against said buck stays, a rib projecting from said plate opposite said buck stays 55 over and spaced a slight distance above said arch, and a downward extension of said plate below said rib supporting, and at substantially a right angle to the thrust of said arch.

3. An arch supporting skew back comprising a flat plate member having a portion adjacent one edge inclined at an angle to the plane of said plate and a rib member adjacent the intersection of the planes of the 65 flat and inclined portions.

4. In a furnace, a roof arch, upright stays at the sides of the furnace, and a skew back retaining member for said arch having an upright plate portion extending 70 above the arch of said furnace and resting against the buck stays and a portion extending normal to the thrust of said arch and supporting one edge of said arch.

5. In a furnace, a roof arch, upright stays 75 at the sides of said furnace, and a skew back retaining member for said arch having an upright plate portion extending above the arch of said furnace and resting against the buck stays, a portion extending normal 80 to the thrust of said arch and supporting one edge of said arch, and a rib member extending from said skew back immediately above said arch.

FRANK L. ANTISELL.
